UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

MIXING-MACHINE.

1,122,659.

Specification of Letters Patent.

Patented Dec. 29, 1914.

Application filed April 20, 1914. Serial No. 833,147.

To all whom it may concern:

Be it known that I, THOMAS J. STURTEVANT, a citizen of the United States, residing at Wellesley, in the county of Norfolk 5 and State of Massachusetts, have invented or discovered certain new and useful Improvements in Mixing-Machines, of which the following is a specification, reference being had therein to the accompanying 10 drawings.

This invention relates to certain improvements in the so-called "Hunso" mixer or mixing machine covered by U. S. Patent No. 985,299, dated Feb. 28, 1911, and has for 15 its object to provide convenient means for discharging the mixed material, as well as to improve the efficiency of the machine, and to avoid objectionable friction which results from the construction hereinbefore in 20 use, and in which some of the material leaks out between the rotating drum and the surrounding stationary housing, so that it scrapes around between the drum and housing, causing more or less friction.

25 In carrying the present invention into effect the rotating drum is provided with a series of openings closed by swinging doors which, when the means for holding them closed is released, will open by gravity for 30 the discharge of the material as the openings and doors approach the lower side of the drum in its rotation, and will also be closed by gravity as the openings and their doors move upward, such gravity-closing 35 being preferably assisted by means which will force the doors tightly to closed positions if their weight is not sufficient to effect this result.

The invention consists in the novel features as indicated by the claims at the end 40 of this specification.

In the accompanying drawings Figure 1 is a side view of a mixer embodying one form of the present invention. Fig. 2 is an 45 end view of the same looking from the right of Fig. 1. Fig. 3 is a cross section of the mixer on line 3—3, Fig. 1, and Figs. 4 and 5 are detail views of one of the swinging doors and related parts.

50 Referring to the drawings, 12 denotes a suitable frame or base provided with standards 13 which afford bearings for a driving shaft 14 provided with a driving pulley 15, a pinion 16 and supporting wheels 17. The 55 pinion 16 meshes with a gear ring 18 se-

cured to and encircling the rotating drum or cylinder 19 which is provided with rings or flanges 20 running on wheels 17 and similar wheels 21 suitably journaled on the frame or base 12. From this it will be understood that when the driving shaft 14 is in motion the drum or cylinder 19 will be rotated for the mixing operation. The material to be mixed is fed to the mixing drum or cylinder from a hopper 22 discharging 60 into said drum or cylinder and sustained by suitable supports 23.

Surrounding the central portion of the rotating drum or cylinder 19 is a casing 24 properly supported on the frame or base 12 65 and open at its bottom for the discharge of the mixed material. The rotating drum or cylinder 19 is provided at its middle portion, within the casing 24, with a series of openings 25 normally closed by swinging 70 doors 26. Within the said casing 24 is a circular track consisting of fixed and movable parts or sections 27 and 28 against which run rollers 29 carried by levers 30 pivoted to the swinging doors 26.

Between the levers 30 and the doors 26 are interposed springs 31 which normally press the said levers outward away from the said doors, the movements of said levers under the action of said springs being, however, 85 limited by adjustable stop screws 32 tapped in lugs 33 on the levers 30 and abutting against the swinging doors 26; the said stop screws being secured in any desired positions of adjustment by lock-nuts 34. The 90 springs 31 hold the levers 30 yieldingly in place so that in case any obstructing material gets between the door frames and the doors, to prevent the latter from closing fully, breakage will be avoided.

The swinging doors 26 are pivoted on rods 35 supported by lugs 36 bolted to the drum or cylinder 19, said rods passing through ears 36' on the said doors, the doors and their supports being thus removable and replaceable as units, which is important in 100 making repairs.

The movable or swinging part or section 28 of the track, against which the rollers 29 run, is pivoted at 37 to the casing 24, the 105 said swinging section having connected therewith a handle 38, by which it may be operated, and an arm 39 provided with a counterbalancing weight 40 to facilitate the manual operation of the said swinging sec- 110

tion. The pivoted latch 41 is provided with suitable notches 42 for engagement with a pin 43 on the handle 38, so that by virtue of this construction the swinging section 28 5 may be held in either open or closed position.

From the foregoing it will be understood that when the swinging section 28 of the track is in the position denoted by dotted 10 lines in Fig. 3 the rollers 29 will engage said track throughout the rotation of the drum or cylinder 19, and will thus hold the swinging doors 26 tightly closed during the mixing 15 operation. When, however, the material within the drum or cylinder has been thoroughly mixed and it is desired to discharge the same from the drum the swinging section 28 of the track is moved from the position shown in dotted lines to the position 20 shown in full lines in Fig. 3, so that when the rollers 29 pass downward below the fixed portion 27 of the track against which they run the swinging doors will be released and they will then be free to open by gravity for 25 the discharge of the material at the lower side of the drum; and after having been thus opened they will be closed by gravity as they move upward on the right side of the drum (looking at Fig. 3), and this gravity-closing movement may be assisted by the 30 engagement of the rollers 29 with the part 28 of the swinging section of the track.

The rotating drum or cylinder 19 is provided internally at its opposite end parts 35 with a series of inclined wings 44 fixed to the lifting flanges or buckets 45, these inclined blades 44 serving to force the material toward the central or middle part of the drum where the openings 25 are located, as 40 in the machine of Patent No. 985,299, hereinbefore referred to, so that the material within the drum may be readily discharged, when desired, through the openings at the middle portion of the drum.

45 The improved machine is more especially intended for use in mixing fertilizers, but may be used for other purposes, as will be understood.

The invention is not to be understood as 50 being limited to the details of construction herein shown and described, as such details may be varied widely without departing from the essence of the invention.

Copies of this patent may be obtained for five cents each, by addressing the "Commissioner of Patents, Washington, D. C."

Having thus described my invention I claim and desire to secure by Letters Pat- 55 ent:

1. A rotatable mixing drum provided with circumferential discharge openings, combined with swinging doors to close said openings, said doors being arranged to open 60 and close by gravity, means for holding said swinging doors closed, when desired, and means for forcing said doors to closed position in assisting the gravity-closing action.

2. A rotatable mixing drum provided at 65 or near its middle portion with circumferential discharge openings, combined with swinging doors to close said openings, said doors being arranged to open and close by gravity, means for holding said swinging 70 doors closed, when desired, and means for forcing said doors to closed position in assisting the gravity-closing action.

3. A rotatable mixing drum provided at 75 or near its middle portion with circumferential discharge openings, combined with swinging doors to close said openings, said doors being arranged to open and close by gravity, a yieldingly mounted pivoted arm carried by each of said doors, said arms being each provided with a roller, and a circular track surrounding said drum and against which track the rollers may run, so as to force said doors to tightly closed positions, after they have been opened, as also to hold them closed.

4. A rotatable mixing drum provided with circumferential discharge openings, combined with swinging doors to close said 90 openings, said doors being adapted to be opened and closed by gravity, a circular track surrounding said drum and comprising a fixed and a swinging section, means on said doors to engage said track for the purpose of holding the said doors closed, and means whereby said swinging section may be adjusted to a position to release said holding means when it is desired that the doors should open.

In testimony whereof I affix my signature, 95 in presence of two witnesses.

THOMAS JOSEPH STURTEVANT.
